FIG. - 10

FIG. - 11

FIG. - 12

FIG. - 13

FIG. 1 is a perspective view of a block for planter and wall construction showing my new design;

FIG. 2 is a top plan view thereof;

FIG. 3 is a front elevational view thereof;

FIG. 4 is a side elevational view thereof;

FIG. 5 is a perspective view of a modified form of the block for planter and wall construction shown in FIG. 1, wherein the cylindrical end sections are full height;

FIG. 6 is a top plan view of the modified form of FIG. 5;

FIG. 7 is a front elevational view of the modified form of FIG. 5;

FIG. 8 is a side elevational view of the modified form of FIG. 5;

FIG. 9 is a perspective view of a further modified form of the block for planter and wall construction shown in FIG. 1, wherein a single cylindrical end section of full height is employed;

FIG. 10 is a top plan view of the modified form of FIG. 9;

FIG. 11 is a front elevational view of the modified form of FIG. 9;

FIG. 12 is a right side elevational view of the modified form of FIG. 9; and

FIG. 13 is a left side elevational view of the modified form of FIG. 9.

This is a continuation-in-part of Design application Ser. Nos. D-5903, D-7753 and D-7754, filed Feb. 21, 1967, and July 10, 1967, and now all abandoned.

I claim:

The ornamental design for a block for planter and wall construction, substantially as shown and described.
